UNITED STATES PATENT OFFICE.

ABRAHAM SHELLMAN, OF CHARLESTON, MICHIGAN.

SPRING-TOOTH.

SPECIFICATION forming part of Letters Patent No. 291,946, dated January 15, 1884.

Application filed October 19, 1883. (No model.)

To all whom it may concern:

Be it known that I, ABRAHAM SHELLMAN, a citizen of the United States, residing at Charleston, (Galesburg P. O.,) county of Kalamazoo, 5 State of Michigan, have invented new and useful Improvements in Spring-Tooth Harrows, of which the following is a specification.

My invention consists in an improved spring-tooth, the object being to produce a tooth which 10 shall be both useful and durable, as hereinafter described.

In the drawings forming a part of this specification, Figure 1 shows the tooth in perspective connected with the beam of a harrow-frame; Fig. 2, a cross-section of the tooth-beam and broken edge view of lower portion of the tooth, and Fig. 3 a bottom view of the tooth-beam.

The tooth-beams are made half-round on the 20 under side. Any desirable style of harrow-frame may be used. The tooth has a curved portion adapted to fit the rounded under side of the tooth-beam B, as in other styles of spring-teeth, and it extends therefrom above and between said beam and the next adjacent beam, 25 which feature is shown in the prior state of the art as well; but the bow of my tooth above and between the beams is bell-shaped, and it extends from said bell-bow downward on a like curve as the other side, but oppositely

turned, and terminates in a working end on a level, or substantially so, with the secured end c at the other side. The tooth or the tooth-beam may be canted forward, to cause the working-point to enter the ground during the 35 operation. With such a style of tooth, when unduly-hard soil is met, the forward portion will spring back and rest against the rear portion in front of the tooth-beam, as indicated by dotted lines in Fig. 1. The strain 40 on the tooth is then exerted on the working end, making it an entirely-rigid tooth for the time it is engaged in the hard soil.

Such teeth do not catch straw and like litter as readily as other styles of bowed spring-teeth. 45

What I claim is—

A spring harrow-tooth consisting of a bell-bow located between the tooth-beams, provided with two downwardly-extending ends on a like 50 but oppositely-turned curve, one of said ends forming the working and the other the secured portion, substantially as set forth.

In testimony of the foregoing I have hereunto subscribed my name in the presence of 55 two witnesses.

ABRAHAM SHELLMAN.

Witnesses:

B. H. McCAIN,
O. N. GIDDINGS.
